[57] ABSTRACT

A speed control regulator for a closed-cycle displacer type hot gas engine comprising a separate heating device situated between the regenerating device and the hot end of the displacer cylinder, a passageway bypassing the heating device by leading directly from the regenerating device into the hot end of the displacer cylinder, an externally controlled variable valve which determines what portion of the working gas, if any, will bypass the heating device when being transferred into the hot end of the displacer cylinder, and nonvariable valves which allow all of the working gas to bypass the heating device when being transferred out of the hot end of the displacer cylinder. The hot end of the displacer cylinder is provided with insulation, becoming a mere repository for hot gas, as opposed to an externally heated adjunct to the heating device, in order to obtain rapid regulator response over a wide range of engine speeds. The total mass of gas within the engine's working chambers may remain constant at all speeds.

SPEED CONTROL APPARATUS FOR HOT GAS ENGINE

BACKGROUND OF THE INVENTION

This invention relates to a means of regulating the speed and power of a closed cycle displacer type hot gas engine.

Various solutions to the problem of speed and power regulation in such engines have been suggested before. In some designs regulation has been accomplished by variation of the average pressure, and thus the mass, of the gas within the engine's working chambers. This method is efficient but involves cumbersome re-compressing equipment and storage tanks, as well as a complicated valve system. Considerable weight is thus added to the engine. Other designs maintain a constant average pressure but change the phase angle of the displacer and power pistons, or increase the dead space volume by communicating the power cylinder with another chamber. These last described methods can also be complex, and they generally decrease thermal efficiency.

The primary aim of this invention is to provide a simple, efficient, and lightweight regulator system for the closed-cycle displacer type hot gas engine, which will enhance the suitability of this type of engine for vehicular and other portable uses.

Other aims, features, and advantages will be apparent in the description, below.

SUMMARY OF INVENTION

This invention is a speed regulator for a closed-cycle hot gas engine of the displacer type. The total mass of gas within the working chambers of the engine may remain constant at all times. Speed is regulated by regulating the heat transferred to the working gas during any complete working cycle. Heat transfer is controlled by varying the portion of working gas that passes through the separate heating device of the engine. A passageway is provided which bypasses the heating device by directly connecting the hot end of the regenerating device with the hot end of the displacer cylinder. The flow of working gas through this passageway is varied by an externally controlled variable valve.

BRIEF DESCRIPTION OF THE DRAWINGS

FIG. 1 is a schematic diagram of a hot gas displacer type engine constructed in accordance with this invention.

FIG. 2 is a detailed sectional view of the basic parts of the invention.

FIG. 3 is a bottom view of the valve body illustrated in FIG. 2.

FIG. 4 is a view of the combined variable nonvariable valve.

DESCRIPTION OF THE PREFERRED EMBODIMENT

This invention is applicable to a closed-cycle hot gas engine of the displacer type. In one example of such an engine the displacer piston moves a mass of working gas from the cool end of the displacer cylinder, where it has been compressed by the power piston, through a cooling device, a regenerating device, and a heating

device, and then into the hot end of the displacer cylinder. The power piston then expands the now-heated working gas and in this process some of the heat is converted into mechanical energy. The displacer piston then moves the gas back through the heating device, regenerating device, and cooling device into the cool end of the displacer cylinder and the cycle is completed.

The heating device can be a set of passageways with a large surface area/volume ratio, such as a set of small tubes, heated by a burner. The regenerating device can be a suitable passageway filled with small diameter steel wire, or other material, which can absorb and store heat from the gas as it passes through in one direction and transfers the heat to the gas as it passes through at a lower temperature in the other direction. The cooling device can be a set of passageways with a large surface area/volume ratio cooled by a water jacket.

According to the invention, the total mass of gas within the engine's working chambers may be maintained at a constant level. Unlike the usual hot gas engine design, all external heat is added to the gas in the heating device; the hot end of the displacer cylinder is merely an insulated storage space for hot gas. A short passageway leading from the regenerating device directly into the hot end of the displacer cylinder, thus bypassing the heating device, is provided. A variable valve, externally controlled, situated between the regenerating device, the heating device, and this passageway, determines what portion of the working gas will bypass the heating device when the displacer is transferring the gas to the hot end of the displacer cylinder.

By thus controlling the mass of gas that is passed through the heating device during any engine revolution, and by further providing that heat is transferred into the gas only in the heating device, the variable valve can control the heat input, and thus the power output, of the engine over a wide range of speeds.

The linkage operating the variable valve which is the speed controller can also control the burner output, through obvious means, so the burner will supply less heat as more of the working gas bypasses the heating device. The heating device will therefore be maintained at a nearly constant temperature. Other obvious means, such as a thermostatic control, could also be used to maintain this constant temperature in the heating device.

Use of an insulated displacer cylinder hot end avoids the lag in engine response to a change in the variable valve setting that would be expected were the hot end externally heated by the engine's burner. This lag would result from two facts: That a displacer cylinder hot end is necessarily a large mass of metal in relation to its heat transfer ability, and that the mass of gas flowing into the hot end remains constant although its average temperature varies with the setting of the variable flow valve. Were the valve setting changed to lower engine speed, the burner would put out less heat and the average temperature of the gas entering the hot end would be reduced, but the hot end itself, due to its mass/heat transfer ratio, would take some time to reach a new equilibrium temperature. Engine speed would continue to decelerate until this new equilibrium temperature was established.

A similar lag would be expected upon engine acceleration because of the time required for the displacer cylinder hot end to reach a new, higher temperature. The heating device itself would not be subject to this problem because it is being readily maintained at a nearly constant temperature, as explained above.

The use of an insulated displacer cylinder offers the additional advantage of allowing a wider range of speed control. Since the variable valve can readily bypass substantially all of the gas flowing into the hot end of the displacer cylinder around the heating device, it can control a very wide range of heat input to the engine when, as in this invention, all heat input occurs in the heating device. However, were the hot end of the displacer cylinder also heated by the burner, the heat added to the working gas by heat transfer in this cylinder would remain nearly constant at all times (except for the slow effect of changes in burner output, as mentioned in the preceding paragraphs) and beyond the control of the variable valve, thus limiting the speed range controlled by the valve.

In a design requiring an insulated hot end for the displacer cylinder and a direct bypass passageway between the hot end of the regenerating device and the hot end of the displacer cylinder, it is at once advantageous and convenient to modify the usual hot gas engine gas flow pattern. It would be needlessly wasteful of engine power to force the expanded, hence cooled, gas from an insulated displacer cylinder back through the high flow resistance of the heating device, only to pick up heat that would be immediately thereafter lost to the regenerating device, when a short, direct passageway already exists between the displacer cylinder and the regenerating device, suitable for transferring all the gas out of the hot end of the displacer cylinder. Not only can the flow resistance of the heating device be avoided by using this passageway, but flow resistance can also be reduced in the regenerating device because it can be made smaller, having less heat to store.

The desired flow pattern can be provided by use of nonvariable valve means interposed between the heating device, the regenerating device, and the passageway. This nonvariable valve means can direct all the gas that is moving toward the hot end, and that is not already leaked into the passageway by the variable valve, through the heating device; and it can direct all gas flowing out of the hot end through the passageway.

The invention will be explained more fully with reference to the accompanying drawings, which represent one example thereof.

In FIG. 1, the displacer piston 3, divides the displacer cylinder into an insulated hot end, 5, and a cool end, 33. The power piston, 1, is shown operating in a separate cylinder, but this is for clarity only, and the invention is equally applicable to engines where both the displacer piston and the power piston operate in the same cylinder. The heating device, 9, connects the hot end of the displacer cylinder, 5, with the valve body, 13. A passageway, 7, also connects the hot end of the displacer cylinder with the valve body, 13, bypassing the heating device, 9. The lower portion of the valve body is connected to the regenerating device, 23. The cooling device, 25, is connected to the lower end of the regenerating device and the cool end of the displacer cylinder, 33.

The valve body, 13, contains the variable valve, 19, which is shown as a combined annular poppet/rotary face valve. In fact, valve 19 as shown is a dual purpose valve: It functions as the variable valve controlling the engine speed, and also as one of the two nonvariable valves required to assure that all the gas bypasses the heating device when being transferred from the hot end to the cool end of the displacer cylinder. The combination of these two functions in one valve is not at all essential to this invention, but it does simplify the design, and for that reason is preferred.

In its function as the variable valve, valve 19 performs when seated as a rotary face valve. FIGS. 3 and 4 best shows this function. Its rotary position can be controlled by providing a sliding splined connection with valve rod 27, the rotary position of which can in turn be externally controlled by obvious means. The means shown as one example in FIG. 1 is a splined adjuster cap, 31, which fits over a splined portion of the valve rod, 27, and which can be externally rotated. Dual geared crankshafts, 29, together with a scotch yoke reciprocating mechanism, 30, allow the valve rod to be so controlled by its bottom extremity.

In its function as one of the two nonvariable valves, valve 19 performs as an annular poppet valve, actuated vertically by valve rod 27, which is itself actuated by eccentrics on the crankshafts. The other nonvariable valve, 11, is shown as a circular poppet valve actuated by the same valve rod. The valve rod, 27, has an increased diameter between valves 19 and 11, better seen on FIG. 2, which allows both valves to be seated when said rod is in the center of its travel, but which immediately opens valve 11, or valve 19, as it moves above or below its center of travel, respectively.

Referring again to FIG. 1, the operation of an engine with the speed regulator apparatus is as follows: Beginning with the displacer piston, 3, at the top of its stroke, and the power piston, 1, completing its compression stroke, valve rod 27 moves upward, opening nonvariable valve 11. The displacer piston, 3, moves downward forcing the gas from the cool end, 33, through cooling device 25, through regenerating device 23, through the open central portions 21 of valve 19, thence through the open portions of central chamber 17 of valve body 13, around nonvariable valve 11, through heating device 9, and into the hot end of the displacer cylinder, 5.

As the gas flows through the open central portions 21, of valve 19, and depending upon the rotary position of valve 19, a variable amount of gas will be leaked directly into annular chamber 15, thence it will pass through passageway 7, into hot end 5. The larger the amount of gas that is thus allowed to bypass the heating device, the lower the engine speed and power.

The flow pattern remains as described until the displacer piston, 3, reaches the bottom of its stroke. By this time the power piston, 1, is completing its expansion stroke, and the gas, which is almost entirely in the hot end of the displacer cylinder or its extension over the power piston, is expanded and somewhat cooled. The valve rod, 27, then moves downward, closing nonvariable flow valve 11, and opening valve 19. As the displacer piston moves upward it forces all the gas from hot end 5, through passageway 7, into annular chamber 15, around the now-opened valve 19, through the

regenerating device 23, through the cooling device 25, and into cool end 33, thus completing the cycle.

FIGS. 2 and 3 illustrate the valve body and valves in greater detail than FIG. 1. Number references are identical with FIG. 1, with several additional references.

In FIG. 3, which shows the valve body from the bottom, with valve 19 and the valve rod 27 removed, the blocked portion 35, of annular chamber 15 can be clearly seen. The blocked portions 37 of central chamber 17 can also be seen. The illustrated surfaces of the blocked portions of both chambers are flush with the annular chamber valve seats, 45, for valve 11. When valve 11 is seated, the blocked portions of both chambers can form a seal with corresponding portions of valve 19.

FIG. 4 shows combination annular poppet/rotary face valve 11, including the blocked central portions, 39; the open central portions, 21; the outer sealing portions, 41; and the outer relieved portions, 43.

Comparing FIGS. 3 and 4 it will be seen how valve 11 functions as the variable valve when it is seated on valve body 13. In one position, the outer sealing portions, 41, of the valve completely seal the corresponding open portions of annular chamber 15. At the same time the open central portions, 21, of the valve leave completely unobstructed the open portions of the central chamber, 17, of the valve body. This position represents maximum engine speed and power, since all gas going into the hot end of the displacer cylinder is being directed through the heating device.

By rotating the valve against the valve body in either direction, open portions of annular chamber, 17, are exposed by outer relieved portions, 43, of the valve. At the same time, blocked central portions, 39, of the valve cover a proportional part of the open portions of central chamber, 17, of the valve body. After 90° of rotation, the open portions of annular chamber, 15, will be completely exposed and the open portions of central chamber, 17, will be completely blocked, in which case the engine will be stopped since all the gas is bypassing the heating device.

What I claim is:

1. A speed control apparatus for a hot gas engine of the type which has a displacer piston operating in a gas filled displacer cylinder having a hot end and a cool end, and which has a cooling device connected at its first end to the cool end of said displacer cylinder and at its second end to the first end of a regenerating device, said regenerating device connected at its second end to the first end of a heating device, and said heating device connected at its second end to the hot end of said displacer cylinder, so that said cooling device, regenerating device, and heating device together provide a passageway for said gas to be transferred by said displacer piston from one end of said displacer cylinder to the other end, said speed control apparatus comprising:

a. Passageway means, situated so as to connect the hot end of the displacer cylinder and the second end of the regenerating device, for putting the hot end of said displacer cylinder in direct communication with the second end of said regenerating device, thus providing a gas flow path bypassing said heating device, and,

b. Variable valve means, situated at said passageway means, for controllably varying the gas flow resistance through said passageway means, by which a portion of the gas flowing from the cool end of the displacer cylinder to the hot end of said cylinder can be variably and controllably diverted from said regenerating device through said passageway means directly into the hot end of said displacer cylinder, bypassing said heating device.

2. A speed control apparatus, as recited in claim 1, where the variable valve means further comprises means, situated at said heating device, for controllably varying the gas flow resistance through said heating device.

3. A speed control apparatus as recited in claim 2, where there is additionally provided insulation means positioned at the walls of the hot end of the displacer cylinder, for reducing the heat transfer into or out of said hot end, by which said hot end becomes a mere repository for hot gas, as distinguished from a device in which additional heat is transferred to said gas.

4. A speed control apparatus, as recited in claim 3, where there is additionally provided nonvariable valve means, situated between said regenerating device and said passageway means, alternately opening and closing said passageway means to gas flow but operating independently of said variable valve means, by which gas flowing from the cool end of the displacer cylinder to the hot end of said cylinder is directed through the heating device when said nonvariable valve means is in the closed position, and by which gas flowing from the hot end of the displacer cylinder to the cool end of said cylinder may pass through said passageway means when said nonvariable valve means is in the open position.

5. A speed control apparatus, as recited in claim 3, where there is additionally provided nonvariable valve means situated between said regenerating device, said heating device, and said passageway means, alternately opening and closing said passageway means and said heating device to gas flow but operating independently of said variable valve means, by which gas flowing from the cool end of the displacer cylinder to the hot end of said cylinder is directed through said heating device, and by which gas flowing from the hot end of the displacer cylinder to the cool end of said cylinder is directed through said passageway means, bypassing said heating device entirely.

6. A speed control apparatus, as recited in claim 5, in which the nonvariable valve means comprises:

a. A valve body having a central cylindrical chamber in communication with the regenerating device and the heating device, with a valve seat in said cylindrical chamber, and having a concentric annular chamber opening at one end toward said regenerating device with valve seats at said open end, said annular chamber in communication with said regenerating device and said passageway means, and

b. A circular poppet valve situated in said valve body so as to seal the valve seat in the central cylindrical chamber of said valve body when the gas pressure in the heating device is greater than that in the regenerating device, and

- c. An annular poppet valve situated in said valve body so as to seal the valve seats in the concentric annular chamber of said valve body when the gas pressure in the regenerating device is greater than that in the passageway means, and
  - d. Valve actuating means for opening and closing said poppet valves in accordance with the movement of the displacer piston.
7. A speed control apparatus, as recited in claim 6, in which the variable valve means comprises:
- a. Annular chamber blocking means situated in and filling portions of the open end of the annular chamber in the valve body, for providing a face seal with any corresponding portions of the annular poppet valve when said valve is seated, and
  - b. Central chamber blocking means situated in and filling portions of the central cylindrical chamber of the valve body, for providing a face seal with any corresponding portions of the annular poppet valve when said valve is seated, and
  - c. Annular poppet valve relief means, situated in the outer sealing portions of the annular poppet valve

- which seal the annular chamber of the valve body, for allowing gas to pass through the relieved portions of said valve when seated, and
- d. Annular poppet valve blocking means, situated in the central portion of said valve, for providing a face seal with the central chamber blocking means when said valve is seated, said annular poppet valve blocking means arranged in relation to said relief means in such a way so that, when said annular poppet valve is seated and rotated about its central axis, the gas passage area between the central chamber blocking means and the annular poppet valve blocking means decreases as the gas passage area between the annular chamber blocking means and the annular poppet valve relief means increases, and
  - e. Rotation means for controlling the rotary position of said annular poppet valve in relation to the valve body and the annular and central chamber blocking means, independently of the seating and unseating of said annular poppet valve.
